UNITED STATES PATENT OFFICE.

CHRISTOPHER J. MOGAN, OF CHARLEROI, PENNSYLVANIA, ASSIGNOR TO PITTSBURGH STEEL CO., OF PITTSBURGH, PENNSYLVANIA, A CORPORATION OF PENNSYLVANIA.

COTTON-TIE-BUNDLING MACHINE.

1,087,810.

Specification of Letters Patent.

Patented Feb. 17, 1914.

Application filed March 12, 1913. Serial No. 753,829.

To all whom it may concern:

Be it known that I, CHRISTOPHER J. MOGAN, a citizen of the United States, and resident of Charleroi, in the county of Washington and State of Pennsylvania, have invented a new and useful Improvement in Cotton-Tie-Bundling Machines; and I do hereby declare the following to be a full, clear, and exact description thereof.

10 My invention relates to a machine for bundling cotton-ties or other articles to which it may be found applicable.

The object of my invention is to provide a simple and convenient form of apparatus 15 by which the assembled cotton-ties may be quickly doubled without manual labor and held in this position while the binding ties are adjusted, thereby lessening the cost and doing away with the severe labor heretofore 20 involved in this operation.

To these ends my invention comprises the novel features hereinafter set forth and claimed.

In the accompanying drawings, Figure 1 25 is a plan view of my improved machine; Fig. 2 is a side elevation; Fig. 3 is a like view showing the hinged section swung over into doubling position; Fig. 4 is an end view at the right hand side of the drawing, the 30 table portion being in cross-section on the line 4—4 Fig. 1; Fig. 5 is an end view at the left hand side, the movable arm being in cross-section on the line 5—5 Fig. 1; and Fig. 6 is an enlarged section showing the 35 manner of introducing the binding tie.

Referring to the drawing the numeral 2 designates a suitable base plate for the hydraulic cylinder 3. This cylinder is provided with the plunger 4 to which is connected the rack-bar 5. This rack-bar moves in suitable guides 6 in the base-plate. The rack-bar 5 engages the toothed segment 7 which is keyed to the shaft 8 which turns in suitable bearings 9 in the frame. The 40 hinged or swinging section 10 of the support for the ties, is provided with the collars 11 which are keyed to the shaft 8. An arm 11a extends out from the hinged section 10 and said arm carries the counterweight 12. The swinging section 10 has the shelves 13 spaced apart, said shelves being provided with the depressions 14 which receive the ties. The shelves are provided with the 45 openings 15 to receive the pintles 16 to lock or hold the ties in position when the swing-

ing section 10 is swung over to double the ties.

The stationary section 17 of the tie-support is arranged in line with the shelves 13 and this stationary support is carried by the bed 18. The section 17 projects out beyond the main body of the swinging section 10 for the purpose more fully hereinafter set forth. Arranged at intervals on the section 17 are the seats 19 to receive the ties. These seats 55 have the guideways 20 through which the binding ties 21 are passed beneath the bundle of ties, as clearly indicated in Fig. 6.

A bending-pin 22 is inserted in a seat in the shaft 8 said pin being freely removable 70 therefrom.

In the operation of the machine, the cotton-ties, when cut to proper lengths, are placed one on top of the other until the proper number to form the bundle have been 75 assembled, whereupon the ties are laid on the support comprising the swinging section 10 and the stationary section 17, three bundles of ties being illustrated as placed thereon as shown in Fig. 6. When the ties 80 have been placed upon the support in this way, the water or other motive power is introduced into the cylinder 3 and the rack-bar 5 is advanced. The movement of the rack-bar engaging the segments 7 rotates the 85 shaft 8 and by the rotation of said shaft, the swinging section 10 is swung over until it takes the position indicated in Fig. 3, the cotton-ties being around the bending pin 22, as indicated in Fig. 3. As the swinging 90 section 10 is not in line with the stationary section 17 the pin 22 does not in any way interfere with the bringing of the two sections over into the folded position indicated in Fig. 3. In this way the ties are doubled 95 over on each other. The binding-ties 21 are then inserted in the depressions 20 in the seats 19, and said ties are guided by the curved face 26 so as to be turned upwardly and when the binding-tie has been inserted 100 in this way, its ends are tied or twisted to bind the cotton-ties securely together in one bundle. When this has been done the rack 5 is withdrawn and the swinging section 10 is swung back to its normal position leaving 105 the cotton-ties resting on the stationary support 17. The bending pin 22 is then withdrawn and the bundle is removed from the support 17 ready for shipment.

By the above apparatus, I provide a sim- 110

ple and convenient form of mechanism by means of which the cotton-ties are doubled without manual labor, and the binding-ties readily inserted while the cotton-ties are held in this double position, so that the whole operation is done with great rapidity and ease.

What I claim is:

1. In apparatus for bundling cotton ties or like articles, the combination of a support comprising a stationary section and a swinging section, the stationary section extending out beyond the body of the swinging section, shelves on said swinging section in line with said stationary section, a bending member in the space between the innermost shelf of said swinging section and the inner end of said stationary section, and means for operating said swinging section.
2. In apparatus for bundling cotton ties or like articles the combination of a support comprising a stationary section, a shaft, a swinging section mounted on said shaft, said stationary section extending out beyond the main body of said swinging section, shelves on said swinging sections spaced at intervals and in line with said stationary section, a bending pin entering a seat formed for it within said shaft and means for rotating said shaft.
3. In apparatus for bundling cotton-ties or like articles, the combination of a support comprising a stationary section and a swinging section, shelves on said swinging section spaced at intervals in line with said stationary section, locking devices engaging said shelves, and means for operating said swinging sections.
4. In apparatus for bundling cotton-ties or like articles, the combination of a support comprising a stationary section and a swing-

ing section, shelves on said swinging section spaced at intervals in line with said stationary section, locking pins engaging said shelves, and means for operating said swinging section.

5. In apparatus for bundling cotton ties or like articles, the combination of a support comprising a stationary section and a swinging section, a bending member projecting out from the axis of said swinging section, and means for operating said swinging section.

6. In apparatus for bundling cotton-ties or like articles, the combination of a support comprising a stationary section and a swinging section, a freely removable bending pin extending out from the axis of said swinging section, and means for operating said swinging section.

7. In apparatus for bundling cotton-ties or like articles, the combination of a suitable support comprising a stationary section and a swinging section, means for operating said swinging section, seats at intervals on said stationary section, and openings formed below said seats for the insertion of the binding-pins.

8. In apparatus for bundling cotton-ties or like articles, the combination of a support comprising a stationary member and a swinging member, a longitudinally movable rack-bar connections between said rack-bar and said swinging-member, and means for moving said rack-bar.

In testimony whereof, I the said CHRISTOPHER J. MOGAN have hereunto set my hand.

CHRISTOPHER J. MOGAN.

Witnesses:
